UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR IN TRANSFERRER ARM.

Application filed December 14, 1926. Serial No. 154,804.

This invention relates to improvements in weft detectors mounted in regularly moving transerrer arms of the type shown in patent to Ryon No. 1,372,316 and it is the 5 general object of the invention to make a readily removable detecting element and mounting therefor.

In co-pending application #148,396 filed by Cederlund and Turner there is shown a 10 lever pivoted to a transerrer arm and having a detector mounted thereon both for sliding and angular movement, a light compression spring tending to hold the detector in normal lower position and a pin projecting laterally from the detector cooperating 15 with the spring to return the detector to its normal position. It is a more particular object of my invention to form a detecting element with a shank bent back on itself 20 to cooperate with a retaining finger on the supporting lever, the shank being so proportioned as to permit ready removal and renewal of the detecting element.

With these and other objects which will 25 appear as the description proceeds, my invention relates to the arrangements and combinations of parts hereinafter set forth, and more particularly pointed out in the claims.

30 In the accompanying drawings, wherein a convenient embodiment of my invention is shown.

Fig. 1 is a vertical central section through that portion of the transerrer arm which 35 normally lies over the shuttle and bobbin and having the detector cooperating with a full supply of weft.

Fig. 2 is a view similar to Fig. 1 but with the detector moved to indicating position 40 due to an insufficient supply of weft on the bobbin,

Fig. 3 is a vertical section on line 3-3, Fig. 1,

Fig. 4 is a fragmentary top plan looking 45 in the direction of arrow 4, Fig. 2,

Fig. 5 is a detail horizontal section taken on line 5-5 of Fig. 1, and

Fig. 6 is a detail plan of the detector and adjacent part of the supporting lever there- 50 for, showing the relation of these parts when the detector is being removed.

Referring to the drawings the transerrer arm 10 has a bobbin engaging portion 11 provided with a heel 12 and the yarn en-

gaging tip 13. A slot 14 extends vertically 55 through the portion 11 between side walls 15, which, in addition to being connected by the heel 12 and tip 13, are connected by an elongated web 16.

An indicating plunger 17 is provided with 60 a head which receives the outward thrust of a compression spring 18, said plunger and spring being located in a pocket 19 formed in the web 16. A clip 20 partly closes the mouth of the pocket and retains the spring 65 18, cooperating with the latter in its normal tendency to move the plunger to the right from the position shown in Fig. 1. A latch 21 pivoted as at 22 in vertical slot 14 has a hook 23 proportioned to enter a notch 24 70 formed on the left end of plunger 17 to hold the latter normally as shown in Fig. 1 in non-indicating position. Said latch also has a depending tail 25 and is normally held in the position shown in Fig. 1 by a torsion 75 spring 26 one end of which passes over one of the walls 15 as at 27 and the other end of which lies over the top of the latch as at 28.

A detector supporting lever 29 is pivoted 80 to the transerrer arm as at 30 and is held normally in raised position relatively to the transerrer arm by a light tension spring 31 interposed between said lever and a part of the transerrer arm. A finger 32 cooperates with web 16 to position the lever vertically, and the latter has a vertical portion 33 terminating in a horizontal arm 34 having a slot 35, see Fig. 5. The matter thus far described is substantially the same as shown in the aforesaid application and it cooperates 85 with a magazine of the type set forth in the aforesaid patent to Ryon.

It is to be understood that tension spring 31 holds the lever 29 in raised position until the transerrer arm reaches the bottom of its downward stroke, at which time the inertia of the said lever and the parts supported thereby, will be sufficient to overcome the supporting action of spring 31 and said lever and detector will move toward the surface 90 95 to be detected.

In carrying my present invention into effect I provide the supporting arm 29 with a narrow longitudinal vertical slot 50 open at one end as shown in Fig. 5. The detecting element 51 may be formed of a single piece of flat stock with a lower broadened weft engaging portion 52 provided with

yarn penetrating teeth 53. The upper end of the detecting element 51 is formed with a shank 54 of reduced width but of substantially the same thickness as the member 51, said shank extending upwardly through the slot 50 and being bent back on itself as at 55 to have a downwardly extending end 56 spaced from the main part of the shank. The lever 29 is provided with an upstanding finger 57 normally located between the spaced parallel parts of the shank as indicated in Figs. 1 and 2. I find it desirable also to provide the supporting lever 29 with a second finger 58 which together with the finger 57 forms a notch into which the end 56 of the shank may lie. While I have shown this additional finger 58 yet I do not consider the same necessary as it will suffice to have a notch into which the lower part 20 of end 56 may normally rest.

A light compression spring 59 surrounds the lower portion of the shank and is interposed between the broad shoulder 60 of the member 51 and a washer 61 which engages the under side of the lever 29, said washer being wider than the width of slot 50 and the adjacent part of the lever 29 being substantially perpendicular to the axis of the main part of the shank 54.

The normal action of spring 59 is to return the detector to a position substantially the same as that shown in Fig. 1 relatively to the supporting lever 29, the left end of the member 51 being held against the left end of slot 35 by reason of the fact that end 56 of the shank is off-set from the line of action of the spring 59. So long as sufficient weft is present the teeth 53 will be embedded in the yarn and the detector held against movement along the bobbin. When insufficient weft is present, however, the detector will slide as shown in Fig. 2 to engage tail 25 and lift the hook 23 out of notch 24, thereby permitting spring 18 to move the plunger to the indicating position shown in Fig. 2. As soon as the transerrer arm starts up after indication the spring 59 acts as previously described to return the detector to its normal position.

As previously stated one of the features of my invention is to provide a readily removable detecting element and it will be seen from an inspection of Figs. 1 and 2 that the slot 50 is of sufficient length to permit a detector to be moved away from arm 33 a sufficient distance for the end 56 to lie to the right of finger 57. It is necessary of course in order to accomplish this result to have the compression spring 59 of such length as to permit the detector to move upward relatively to lever 29 so that the bottom of end 56 will pass over the top of finger 57. The ready removal of the detector can then be effected because of the fact that slot 65 35 is open. The upper portion of the shank

is sufficiently narrow to pass through the slot 50. The manner of removing the detector from the supporting element is indicated in Fig. 6.

From the foregoing it will be seen that I have provided a weft detector in a regularly moving transerrer arm wherein the detecting element is readily removable so that the same may be given slight bending adjustment if necessary or may be given any other needed attention or renewed.

Having thus described my invention it will be apparent that changes and modifications may be made therein by those skilled in the art without departing from the spirit and scope of the invention, and I do not wish to be limited to the details herein disclosed but what I claim is:

1. In weft detecting mechanism for a loom having a regularly moving transerrer arm, a carrier lever member pivoted to the transerrer, a detector member mounted on the carrier lever and moved by the latter toward the surface to be detected as the transerrer arm moves downwardly, and complementarily formed connections between the members, said connections including an open notch in one member into which a part of the other member extends.

2. In weft detecting mechanism for a loom having a regularly moving transerrer arm, a carrier member movably mounted with respect to the transerrer, a detector member mounted on the carrier, yielding means interposed between the detector and carrier members to hold the detector member normally yieldingly in position to engage the surface to be detected, and connections between the detector and carrier members normally maintained in operative position by the yielding means but movable against said yielding means to release the detector from the carrier, said connections including an open notch in one member to receive a part of the other member.

3. In a weft detecting mechanism for looms having a regularly moving transerrer arm, a carrier lever pivoted to the transerrer arm, a detecting element mounted on the carrier lever for movement relatively thereto, resilient means interposed between the detecting element and the carrier lever tending to hold said detecting element toward the surface to be detected and means defining complementarily formed loose connections between the element and the carrier lever held normally in position by the resilient means and movable against the action of the resilient means to disconnect and detach the element from the carrier lever.

4. In a weft detecting mechanism for looms having a regularly moving transerrer arm, a carrier member supported by and movably mounted on the transerrer arm, a detector member supported by and movable

with respect to the carrier member, means defining a loose pivotal connection between the members, said means including a reduced portion of one member to extend into a complementarily formed portion of the other member, and resilient means interposed between the members to hold the detector yieldingly in normal position with respect to the carrier member, said resilient means

holding the complementarily formed parts 10 and said parts being separable so that the members are relatively detachable one from the other against the action of the resilient means.

In testimony whereof I have hereunto af- 15 fixed my signature.

RICHARD GREENLEAF TURNER.
